186,321

DESK OR SIMILAR ARTICLE

Bruce L. Carlson, Seattle, Wash.

Application January 28, 1957, Serial No. 44,624

Term of patent 3½ years

(Cl. D33—11)

Fig. 1

Fig. 2

Fig. 3

Fig. 1 is a front perspective view of a desk or similar article, showing my design;

Fig. 2 is a rear perspective view; and

Fig. 3 is a bottom plan view thereof.

The dominant features of my design are shown in full lines.

I claim:

The ornamental design for a desk or similar article, substantially as shown and described.
